UNITED STATES PATENT OFFICE.

KAZIMIERZ JAKUBIEC, OF CHICAGO, ILLINOIS.

SHADE-ROLLER HOLDER AND CURTAIN-ROD BRACKET.

Application filed July 15, 1926. Serial No. 122,571.

The main object of the invention is the provision of shade roller holder which may be adjusted upon the window frame without employing screws or nails to attach the

5 same to the frame.

Another object of the invention is the provision of shade roller holder which is extensible and which fits various widths of window frames.

10 Still another object of the invention is the provision of shade roller holder which operates with the curtain bracket and wherein the latter is adapted for longitudinal sliding movement thereupon for adjusting the 15 position of the bracket depending upon the length of the curtain rod.

A still further object of the invention is the provision of cooperating members which are extensible for fitting various widths of 20 the window frames and which are so constructed as to receive shade roller holder wherein the same may be longitudinally adjusted depending upon the length of the shade roller.

25 With the above general objects in view and others that will appear as the nature of the invention is better understood, the same consists in the novel construction, combination and arrangement of parts herein- 30 after more fully described, illustrated in the accompanying drawings and pointed out in the appended claims.

In the drawings forming a part of this application, and in which like designating 35 characters refer to corresponding parts throughout the several views,

Fig. 1 illustrates the upper end of the window showing the two cooperating devices one on each side of the window;

40 Fig. 2 is a cross-sectional view on horizontal plane through the window frame on one side of the window, showing the top view of the device when the same is attached to the window, and also showing one manner of attaching shade roller thereupon;

45 Fig. 3 is a front elevational view of one of the two devices cooperating with the frame on one side of the window;

Fig. 4 is the end view of one section of 50 the device;

Fig. 5 is the elevational view of the other end of the device;

Fig. 6 is a longitudinal sectional view 55 through one end of the device, showing the manner of attaching the same to the window frame, the view being on line 6—6 of Fig. 2;

Fig. 7 is an elevational view of the two cooperating plates in one section of the device showing the manner of putting the plates together;

Fig. 8 is a top view of the two cooperating plates forming one section of the device, with curtain rod bracket attached thereto;

Fig. 9 is a cross-sectional view through 65 the two cooperating plates on line 9—9 of Fig. 8, illustrating the manner in which curtain rod bracket is mounted upon one section of the device;

Fig. 10 is a perspective view of shade 70 roller holder in association with two cooperating plates of one section of the device upon one side of the window;

Fig. 11 is the top view of the shade roller 75 holder in association with the two cooperating sections of the device; and

Fig. 12 is the side elevational view of the shade roller holder.

As illustrated on Fig. 1 the invention consists of two devices 20 and 21 each cooperating with the frame at each side of the window. Each device consists of a J-shaped plate 22 and another similar plate 23. Said first named plate at its inner or longer end is provided with two outwardly bent projections 24, which are receivable within recesses 25 between teeth 26 on the inner or longer end of plate 23, when the two plates are in cooperating association illustrated on Figs. 2 and 3. Plate 23 at its termination 90 is bent inwardly or towards plate 22 and the bent portion of said plate at a point substantially parallel with the remaining portion of said plate is provided with two opposing grooves 27 from which results a 95 transverse lug 28. Plate 22 is provided with a longitudinal central slot 29, and a similar slot 30 is made in plate 23, which slots substantially register when the two plates are in cooperating association.

To assemble the two plates in an operative association the two plates are held at a right angle, lug 28 inserted within slot 29, and when said lug has cleared the inner face of plate 22, plate 23 is angularly shifted until both plates are longitudinally disposed in relation of each other. Fig. 7 illustrates the relative position of the two plates when the same are in the process of assembly hereinabove mentioned. When the two 110 plates are in longitudinal relation with each other, plate 23 is slightly raised angularly

on vertical plane, and when in that position plate 23 may be longitudinally shifted upon plate 22 for making proper adjustment of the two plates depending upon the width of the window frame. Thereupon plate 23 is brought towards plate 22 until projections 23 fit within the desired pair of recesses 25.

When the two plates are in engagement with each other by virtue of the construction hereinabove described, they will remain in rigid engagement with each other preventing the relative longitudinal sliding movement of one plate in respect of the other, and to disengage the plates for the purpose of making longitudinal adjustment thereof, the mode of attaching the plate hereinabove stated is reversed and plate 23 angularly shifted on vertical plane in respect of plate 22 until projections 24 come out of engagement with plate 23 within recesses 25 as is obvious.

The other end of plate 23 is provided with teeth or serrations 31 which prevent plate 23 from shifting upon the window frame when the two plates are mounted upon the window frame by virtue of the mechanism presently described.

The outer end of plate 22 on its inner face is provided with a stationary plate 32 forming a slot within which slidable plate 33 is received and wherein the same is adapted for longitudinal sliding movement. The outer end of said plate 33 is provided with leg 34 which is angularly disposed in relation of plate 33. The outer face of said leg 34 is provided with projections 35 which are adapted to bite into the side of the window frame for holding the two plates in rigid engagement with the window frame. Said plate 22 at its bent foot portion is provided with a relatively short oblong slot 36 wherein the substantially rectangular extension 37 of nut 38 is adapted to be receivable and whereby said nut 38 is held against rotation within said bent portion of the outer end of plate 22. Rod 39 is loosely mounted by its inner end within leg 34, the portion of said rod cooperating with nut 38 being threaded and receivable within said nut 38, the outer end of said rod 39 being provided with loop 40 providing a handle for manual rotation of the rod. From the construction described it will be apparent that on rotating the rod by means of handle 40 leg 34 is shifted away or toward the frame to engage the same by means of projections 35. Plate 33 remaining within slot formed by plate 32 prevents the rotation of leg 34 when rod 39 is rotated.

From the construction above described it will be seen that the plates 22 and 23 are adapted for rigid mounting upon the window frame, they being held thereupon against shifting by virtue of teeth 31 on

the plate 23 and of the projections 35 on leg 34 which cooperate with plate 22.

As already mentioned the two plates 22 and 23 constitute one portion of the device fitting upon the frame at one side of the window, while similar plates are also arranged upon the frame on the other side of the window, the two parts of the device one on each side of the window being of identical construction, with this understanding that two plates 23 at each side of the window are facing each other or are disposed toward the center of the window, while two plates 22 are each disposed away from the window, as is apparent from Fig. 1 on reference to numeral 40 which indicates the handle on rod 39 cooperating with two plates 22 in each section of the invention. As illustrated on Fig. 4 the bent portion of plate 23 is provided at its upper edge with slot 41 and at its inner end with an aperture 42. Similar slot and aperture are likewise provided at the corresponding plate on the other side of the window with this change that in the last mentioned plate 23 the aperture is at the upper edge thereof while the slot is at the lower edge thereof, reference being made to the fact that the position of plate 23 may vary in respect of the window, as obviously the plate may be at one time positioned at one side of the window while at the other time it may be positioned at the other side thereof. Such a transposition involves only the reversal of the relative position of the plate in respect of the window frame. Roller shade such as 43 of the usual construction has a shaft which at one of its ends is flattened, while its opposite end is round. The flat end of the shaft is receivable within slot 41 at plate 23 on one side of the window, while the round end of shaft such as 44 is receivable within aperture 42 in the corresponding plate at the other side of the window.

Said slot 41 and aperture 42 are employed for affixing shade roller when the same is of the length which substantially corresponds with the width of the window. In case the shade roller is longer than the width of the window, then a special shade roller holder such as illustrated on Figs. 10, 11 and 12 is employed which cooperates with plates 22 and 23 and is in slidable association therewith for adjusting the same in accordance with the length of the shade roller. Said last mentioned shade roller holder embodies a shank 45 having an extension embodying neck portion 46 and a transverse lug 47. When said shade roller holder is in operative engagement with plates 22 and 23 said neck portion 46 remains within slots 29 and 30 of plates 22 and 23, respectively, while the transverse lug 47 remains in abutment with the rear

face of plate 22, preventing the forward shifting movement of said shade roller holder, as seen on Fig. 11.

Said shade roller holder at its base portion is further provided with integrally formed plates 48 which remain at right angle in respect of the shank as clearly seen on Fig. 11. Said plates 48 normally rest upon the front face of plate 23 and prevent angular shifting movement thereof to the same direction to which said plates are disposed. Said plates 48 are provided with lugs 49 which are bent at right angle in respect of plates 48, and consequently remain in parallel relation with the shank 45, as is apparent from Fig. 10. When the shade roller holder remains in operative association with plates 22 and 23 said lugs 49 fit into any pair of recesses 25 between teeth 26 of plate 23 and prevent movement of the shade roller holder longitudinally of the two plates 22 and 23. Said shade roller holder on one side of the window frame is provided with an aperture 50 for receiving the round end of the shaft of the shade roller, while the shade roller holder on the other side of the window at substantially the same point is provided with a rectangular slot for receiving the flat end of the shade roller shaft.

From the hereinabove description it will be seen that each of the shade roller holders on each side of the window may be longitudinally shifted in respect of the plates 22 and 23 in order to accommodate various lengths of shade rollers. In order to dismount the shade roller holder from its engagement with plate 23 the same is tilted in the direction opposite to that toward which plate 48 extends, until lugs 49 come out of engagement with recesses 25. When this is done the shade roller holder may be shifted in slots 29 and 30 and when the desired position is found lugs 49 are positioned within any pair of opposite recesses 25.

The curtain rod bracket designed to cooperate with the device hereinabove described is illustrated in the drawings on Figs. 8 and 9. The same embodies horizontal plate 51 and section 52 bent at a right angle in respect of the plate 51, the said section 52 being designed to abut the rear face of plate 22 when the bracket is in operative association with the device. A short section 53 is bent at a right angle in respect of plate 22 and remains parallel with plate 51. Said section 53 normally passes through slots 29 and 30 of plates 22 and 23, respectively, and has a downwardly bent plate 54 which normally remains in abutment with the front face of plate 23 at the lower portion thereof. Said plate 54 has a horizontal lip 55. The outer or forward end of plate 51 is provided with a downwardly bent plate 56 which has a horizontally disposed section 57, from which runs inclined plate 58 which by its end rests

upon the lower face of lip 55. It is noted that the several plates hereinabove stated comprising the bracket are of springy and resilient material, and thus plate 58 has a tendency to press upwardly, and by virtue of 70 its resiliency it at all time remains in close contact with lip 55.

To remove the bracket from the engagement with plates 22 and 23 plate 58 is manually brought out of engagement with 75 lip 55 and then plates 52, 53 and 54 and lip 55 are passed through slots 29 and 30. When in association with plates 22 and 23 as illustrated on Fig. 9, it is apparent that the bracket is adapted for longitudinal sliding movement for adjusting the same upon plates 22 and 23 depending upon the length of the curtain rod.

The bracket hereinabove described is adapted for carrying great weight due to the fact that plate 51 is supported by the upper edges of plates 22 and 23, while plate 58 resists the downward pull by being in abutment with plate 23.

Plate 59, adapted to be positioned upon the upper face of plate 51 at its outer end is provided with a trough-like section 60 upon which curtain rod 61 is positioned. For strengthening said plate 59 as well as to provide guiding means for plate 59 when the same is extended upon plate 51 skirt 62 is provided at each side of plate 59. The inner end of skirt 62 carries pin 63 with roller 64 disposed thereupon, said pin and roller normally remaining below the plate 51, due to 100 which arrangement the upward movement of inner end thereof is under pressure by weight of the rod 61. From the arrangement described it will be seen that said plate 59 is extensible longitudinally of plate 51 for either bringing the curtain rod to or from the window as may be desirable.

While there is described herein a preferred embodiment of the present invention, it is nevertheless to be understood that minor changes may be made therein without departing from the spirit and scope of the invention as claimed.

What I claim as new is:

1. The device of the type described comprising a pair of plates, said plates being provided with coextensive slots, means upon one of the plates engaging in the slot in the second plate for pivotal and longitudinal sliding movement of the first plate in respect to the second plate, teeth upon the first plate, and means upon the second plate to engage said teeth when the plates are placed in a certain position with respect to each other to hold the two plates in longitudinal adjusted position.

2. The device of the type described comprising a pair of plates, said plates being provided with coextensive slots, means upon one of the plates engaging in the slot in the

second plate for pivotal and guiding longitudinal sliding movement of the first plate in respect of the second plate, teeth upon the first plate, and projections upon the second plate, said projections being adapted to automatically engage said teeth when the plates are placed in a certain position with respect to each other for holding the two plates in longitudinal adjusted position.

10. 3. The device of the type described comprising a pair of longitudinally adjustable plates, said plates being provided with coextensive slots, teeth upon one of said plates, a shade roller holder pivotally and slidably mounted in the slots for adjustment longitudinally of the plates, a transverse lug upon said shade roller holder in engagement with one of said plates for preventing shifting movement of said shade roller holder axially thereof, and lugs upon said shade roller holder selectively and automatically engagable with said teeth when the shade roller holder is placed in a certain position with respect to the plates for holding said shade roller holder in adjusted position longitudinally of said plates.

4. The device of the type described comprising a pair of plates, said plates being provided with coextensive slots, means upon one of the plates cooperating with the slot in the second plate for guiding longitudinal sliding movement of the first plate in respect of the second plate, teeth upon the first plate, projections upon the second plate, said projections being adapted to automatically engage with certain of said teeth for holding the two plates in longitudinal relative adjustment, a shade roller holder mounted in the slots of said plates, said shade roller holder being adapted for adjustment within said slots longitudinally of said plates, and means upon said shade roller holder for automatically engaging said teeth to hold the same in adjusted position.

45. 5. The device of the type described com-

prising a pair of plates, said plates being provided with coextensive slots, means upon one of the plates cooperating with the slot in the second plate for guiding longitudinal sliding movement of the first plate in respect of the second plate, teeth upon the first plate, projections upon the second plate, said projections being adapted to automatically engage with certain of said teeth for holding the two plates in longitudinal relative adjustment, a shade roller holder pivotally and slidably mounted in the slots of said plates, said shade roller holder being adapted for adjustment within said slots longitudinally of said plates, and lugs upon said shade roller holder automatically engaging certain of said teeth for holding said shade roller holder in adjusted position.

65. 6. The device of the type described comprising a pair of longitudinally adjustable plates, said plates being provided with coextensive slots, teeth upon the outer edges of one of said plates, a shade roller holder pivotally and slidably mounted in the slots for adjustment longitudinally of the plates, and means upon said shade roller holder automatically engaging said teeth when the shade roller holder is placed in a certain position with respect to the plates for holding said shade roller holder in adjusted position on the plates.

7. The device of the type described comprising a pair of longitudinally adjustable plates, said plates being provided with coextensive slots, teeth upon the outer edges of one of said plates, a shade roller holder pivotally and slidably mounted in the slots for adjustment longitudinally of the plates, and lugs upon said shade roller holder adapted for automatic engagement with said teeth when the shade roller holder is placed in a certain position with respect of the plates for holding said shade roller holder in adjusted position on the plates.

In testimony whereof I affix my signature.
KAZIMIERZ JAKUBIEC.
